DES. 1953

Elemir J. Key, of Lowell, Mass.

As on to

The Lowell Manufacturing Company, of the same place.

Letters Patent No 1953-Dated June 4th 1864.

Design for a Carpet Pattern.

The schedule referred to in these Letters Patent and making part of the same.

To all whom it may concern,

Be it known that I, Elemir J. Key, of Lowell, in the County of Middlesex and State of Massachusetts, have originated and designed a new Pattern for Carpets or other fabrics, of which the following is a full, clear and exact description, reference being had to the accompanying drawings, making part of this specification.

In corner A, is one fourth of a set figure resting on a plain ground. The bands 1, 2, 3, composed of parallel lines and small blocks, form one fourth of a frame, which encloses the set figure before mentioned. In corner B, the set figure and surroundings are similar to those of corner A.

In corner C, is one fourth of a twelve cornered set figure, resting on a ground of diamond net-work and small crosses enclosed by the band 4 and lace work 5. The figures of corner D, are similar to those of corner C. The parallel bands 6, 7, connect the lace work of corners C and D, and enclose a vine on which rests the leaf 8. 9, 10 are rope like bands to each end of which a rosette is attached. Lying between bands 6 and 9, and 7 and 10, respectively are branches of sprigs, resting on these branches are the figs E, F, composed of a diamond ground work with borders of parallel lines.
